UNITED STATES PATENT OFFICE.

KARL JUNG, OF BERLIN, GERMANY, ASSIGNOR TO THE SAMSONWERK, GESELLSCHAFT
MIT BESCHRÄNKTER HAFTUNG, OF BERLIN, GERMANY, A CORPORATION.

SHAPING-MACHINE.

1,205,899.

Specification of Letters Patent. Patented Nov. 21, 1916.

Application filed December 30, 1914. Serial No. 879,777.

To all whom it may concern:

Be it known that I, KARL JUNG, manager, a subject of the German Emperor, and residing at 58/59 Grossbeerenstrasse, Berlin,

5 State of Prussia, in the German Empire, have invented certain new and useful Improvements in or Relating to Shaping-Machines, of which the following is a specification.

10 This invention relates to shaping machines in which the slide carrying the tool is driven by means of a rocking lever. The rocking lever, which is fulcrumed in the frame of the machine and is moved to and fro by a link, for example, must have an axis of oscillation located both parallel to the driving member and exactly at right angles to the direction of movement of the slide. In spite of the axle of the rocking 15 lever having been mounted very exactly, heretofore it was not possible to prevent the end attached to the slide from executing a small rotatory movement relatively to the slide, and the consequence was that the slide 20 jammed in its guides or the tool was guided inexactly, and this could not be obviated by enabling the rocking lever to move laterally relatively to the slide. According to my invention I obviate these defects by providing between the rocking lever and the 25 slide a connection which without possessing any play in the direction of motion of the slide, admits of the rocking lever turning relatively to the slide.

30 Another object of my invention is to provide a wheel of improved construction for driving the rocking lever. In order to mount this driving wheel in the machine, it was heretofore necessary to insert in the 35 rear wall, in which the wheel is journaled, a bushing of a size corresponding to the diameter of the wheel, or to provide in the front wall an aperture so large that the wheel could be placed through the same.

40 This weakening of the supporting walls of the machine is a serious defect because, when heavy work is being done, the guides of the slide yield and the work is done non-uniformly. According to my invention, the 45 wheel used for driving the rocking lever and its pivot pin are made as two separate members, so that the wheel can be introduced from above and then be connected with its pivot.

50 To these ends, my invention consists in

the construction, arrangement and combination of parts described hereinafter and pointed out in the claims.

Several illustrative embodiments of my invention are represented by way of example 60 in the accompanying drawing, wherein:—

Figure 1 is a vertical cross-section through part of a shaper comprising the improvements according to my invention. Fig. 2 is a side elevation of the upper part 65 of Fig. 1 after the outside wall of the slide has been removed, and Figs. 3, 4 and 5 are vertical cross-sections showing three modifications of the improved connection of the rocking lever to the carriage.

Referring first to Figs. 1 and 2, *a* designates the frame of the shaper and *b* the slide movable on the frame and carrying the tool. The slide is driven by the rocking lever *c* which is provided in known manner with an adjustable sliding bearing *d*, in which the pin *f* of the gear wheel *e* is journaled. When the gear wheel rotates, the lever *c* rocks to and fro and drives the slide *b* with it. In order to prevent any 80 lateral movement of the rocking lever being imparted to the slide, in the arrangement shown in Figs. 1 and 2 the driver *g*, which is otherwise formed in known manner and connected with the slide *b*, is made hollow 85 and provided with an internal thread, into which a threaded member *h* is screwed. A pin *i* goes through the latter and through the forked ends of the rocking lever embracing the driver *g*. The holes in the 90 driver *g* are larger than the diameter of the pin *i*. In this arrangement, in the direction of movement of the slide the rocking lever and the carriage are connected pivotally but without play; as the member in 95 the driver *g* can rotate, however, the rocking lever can turn laterally without the slide participating in such movement, because the pin *i* can move in the holes in the driver *g* which, as mentioned above, are 100 larger than the diameter of the pin.

Figs. 3, 4 and 5 show other modes of attaching the fitting in the driver *g*. In the embodiment shown in Fig. 3, the driver *g* has a smooth hole into which is inserted a 105 smooth pin *k* which is carried vertically but not seized by a screw *m* screwed in from below, so that it can participate with the pin *i* in the turning movement of the rocking lever for the described purpose. In the 110

form shown in Fig. 4, I provide instead of the screw *m* a closure member *n* inserted into guides. In the modification shown in Fig. 5 the pin *k* is carried by a pin *o*, half of which takes into a groove in the pin *k* and half into the driver *g*.

In the construction known heretofore, the driving wheel *e* always had to be inserted through the front or rear wall of the shaper either by inserting into the rear wall in which it was journaled a bushing of a size corresponding to the diameter of the wheel, or by providing such a large aperture in the front wall that the wheel could be passed through it. This weakening of the carrying walls of the shaper was a great disadvantage, because when heavy work had to be done the guides of the carriage yielded and untrue work was the consequence. In order to remedy this defect, according to my invention the gear wheel *e* is no longer made integral with its axle *p* but is attached thereto by means of a screw thread *q* or in other suitable manner. It is consequently possible to place the narrow wheel *e* from above into the interior of the shaper before putting the carriage *b* into place, and then to place the axle *p* into its bearing and to connect the axle and the wheel together. This arrangement also has the advantage that the axle *p* and the wheel *e* can be exchanged independently of one another when one of them becomes worn and, in addition, a more suitable material can be used for the axle which can be hardened.

I claim:

1. In a shaping machine, the combination with the frame, a slide slidable to and fro

thereon, and a lever mounted to rock in the frame, of a hollow driver carried by the slide, a member rotatable in the driver, and a pin carried by said lever and passing laterally through the driver with play and through said member.

2. In a shaping machine, the combination with the frame, a slide slidable to and fro thereon, and a lever mounted to rock in the frame, of a hollow driver carried by the slide, a member screwed into the driver, and a pin carried by said lever and passing laterally through the driver with play and through said member.

3. In a shaping machine, the combination with the frame, a slide slidable to and fro thereon, and a lever mounted to rock in the frame, of a hollow driver carried by the slide, a member rotatable in the driver, means for preventing the member leaving the driver, and a pin carried by said lever and passing laterally through the driver with play and through said member.

4. In a shaping machine the combination with the frame, a slide slidable to and fro thereon and a lever mounted to rock in the frame, of means connecting the lever with the slide and containing two parts turnable against each other about an axis vertical to the sliding movement of the slide the two parts being connected to the lever and slide respectively.

In testimony whereof, I have affixed my signature in presence of two witnesses.

KARL JUNG.
